UNITED STATES PATENT OFFICE.

PETER COOPER HEWITT, OF RINGWOOD MANOR, NEW JERSEY.

COOLING FIREARMS.

1,329,903.

Specification of Letters Patent.

Patented Feb. 3, 1920.

Application filed June 21, 1917. Serial No. 176,014.

To all whom it may concern:

Be it known that I, PETER COOPER HEWITT, a citizen of the United States, and resident of Ringwood Manor, county of Passaic, 5 State of New Jersey, have invented certain new and useful Improvements in Cooling Firearms, of which the following is a specification.

My invention relates to means for cooling 10 firearms of different characters, especially rapid automatic guns employing explosives as the bullet propelling means at such rates that the barrel is apt to become overheated by the heating effect of the powder, and 15 recognizes as of equal importance cooling means to dissipate the heat so generated at such a rate as to prevent undue overheating, and the necessity of the association of the two so as to insure the delivery of the one 20 with the other.

My invention consists in providing means for automatically and definitely associating cooling means with the feed of the explosives and the relation of the cooling means 25 to the explosive cartridges or shells being such as to bear the proper relation of cooling to heating. The cooling means are so associated with the explosives that the cooling means must be supplied to the gun when the 30 explosive or heating means are supplied.

A convenient means for carrying out my invention is to mount upon a belt or tape or in some suitable carrier, cartridges and a container for heat absorbent substances, such 35 as water, or equivalent material, so arranged that the heat absorbent will be fed to the gun in regular relation, with reference to the explosives. In the case of the use of water, for instance, the carriers of water will be so 40 located that the water therein will be fed to the gun so as to cool the barrel from the outside at the required rate with reference to the cartridge feed. The gun has a heat storage capacity which may be utilized for

45 permitting a definite intermittence between the successive explosive supply and cooling supply. Various different methods may be adopted for securing this result, the broad feature of the invention being the inseparable and definite association for delivery 50 for assuring the feeding of the cooling and explosive materials in proper relation and with reference to the permissible heating of the gun.

55 In the accompanying drawings, I have shown one method of applying the invention

Figure 1 showing an alternate arrangement of explosive cartridges and cooling carriers; Fig. 2 showing an arrangement of a plurality of cartridges and a cooling carrier; 60 and Fig. 3 showing a modified arrangement of the elements of Figs. 1 and 2. Referring to the drawing, 1, represents a belt or carrier upon which are arranged explosive cartridges, 2, and at intervals there are placed 65 cooling cartridges, 3; for instance, shells similar to the shells of the explosive cartridges, but containing water or other heat absorbent.

In the drawing the cooling cartridges are 70 shown as being arranged to be fed in equal numbers coincident with the explosive cartridges, but the cooling cartridges may be arranged to feed in any other ratio to the explosive cartridges, such for instance as one 75 cooling cartridge to every three explosive cartridges as shown in Fig. 2, or at any other predetermined ratio. The cooling cartridges may be fed to a chamber other than the gun bore arranged so as to abstract the 80 heat from the barrel.

I have not here shown any particular gun, as the invention may be variously modified to suit the requirements in different cases. Mechanism for producing the simultaneous 85 delivery of the explosive cartridge and the cooling cartridge to their respective chambers in the ratio required for cooling is readily obtainable and the cooling action is insured on account of the inseparable association of the heating and cooling means, in 90 proper proportion and in time of delivery.

I claim as my invention:

1. The method of cooling firearms which consists in associating a separate individually mounted cooling medium with the cartridge supply, and passing the cooling medium and the cartridge supply to the firearms in definite relation to the heating of said firearms. 95

2. In a cartridge feed belt, the combination with a series of explosive cartridges or shells, of interspersed cooling carriers definitely arranged with reference to the explosive cartridges. 100

3. As an article of manufacture, a unitary carrier containing explosive cartridges and cooling cartridges, said cooling cartridges being mounted in said carrier independently of the explosive cartridges. 105

4. In a cartridge feeding device, the combination with a series of explosive cartridges 110

or shells, of cooling carriers definitely arranged with reference to the explosives and separately mounted in said device.

5. The combination in a unitary package, of a plurality of explosive cartridges or shells, and a cooling medium in a separate container mounted independently of the explosive shell.

10. In a cartridge supply device, the combination with a series of explosive cartridges or shells, of separate cooling means definitely arranged with reference to the explosives and mounted in said device independently of the explosive cartridges.

15. 7. A cartridge supply device comprising a plurality of explosive cartridges or shells,

and separate cooling means associated therewith mounted in said device independently of said explosive cartridges.

8. In a cartridge supply device, the combination with a plurality of explosive cartridges or shells, of separate cooling means spaced apart in said device and mounted independently of said explosive cartridges.

Signed at New York in the county of New 25 York and State of New York this 19th day of June, A. D. 1917.

PETER COOPER HEWITT.
